UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

PROCESS OF MAKING STITCH-DOWN SHOES.

1,159,084.

Specification of Letters Patent.

Patented Nov. 2, 1915.

Application filed May 21, 1913. Serial No. 768,975.

To all whom it may concern:

Be it known that I, ADAM H. PRENZEL, a citizen of the United States, residing at Halifax, in the county of Dauphin and 5 State of Pennsylvania, have invented certain Improvements in Processes of Making Stitch-Down Shoes, of which the following description, in connection with the accompanying drawings, is a specification, like 10 reference characters on the drawings indicating like parts in the several figures.

This invention relates to processes of making shoes and is particularly applicable to the manufacture of shoes having outturned 15 uppers and commonly referred to as "stitch-down" shoes.

An object of this invention is to provide an improved process of making stitch-down shoes to the end that the best materials may 20 be utilized without so increasing the cost of the shoe as to make it unprofitable to manufacture.

In the manufacture of stitch-down shoes little attention has been paid, up to the 25 present time, to the fit of these shoes, to so constructing the shoes that they will maintain their shape as they are worn and to so making the shoes that they can be resoled without relasting. One of the reasons why 30 so little attention has been paid to the fit of these shoes is that until recently it has been almost impossible to conform a stitch-down upper to the last and to keep it conformed to the last until the outsole is attached. It 35 has therefore only been profitable to make these shoes in the cheaper grades and of such poor materials in most cases that there has been little occasion for having the shoes repaired, since the shoe as a whole has been in 40 such shape by the time the sole has become worn that it has not been worth repairing. By the improved lasting process disclosed in United States Letters Patent No. 1,117,086, granted November 10, 1914, on my co-pending 45 application Serial No. 725,476, filed Oct. 12, 1912, and by the machine for performing this lasting process disclosed in United States Letters Patent No. 1,117,087, granted November 10, 1914, and No. 1,117,440, 50 granted November 17, 1914, on my co-pending applications Serial Nos. 725,477 and 736,079, filed respectively, Oct. 12, 1912 and Dec. 11, 1912, the problem of lasting stitch-down shoes has been so successfully solved

that it has now become both feasible and 55 profitable to manufacture these shoes of better materials and for the better classes of trade. Up to the present time, stitch-down shoes have been manufactured principally in the children's sizes. The present invention 60 aims to facilitate the manufacture of shoes of this type not only in children's sizes but especially in boys' and men's sizes, and at the same time to provide a process whereby 65 shoes may be made of such neat appearance as to adapt them for the misses' and women's trade.

In carrying out the present invention I contemplate the employment of an insole 70 which can be shouldered or channeled to form a support inside the shoe for the upper, and which, after shouldering, will have a flange of sufficient thickness and strength so that the upper can be secured to it in the lasting operation by staples or other suitable 75 permanent fastenings which will preferably, in the case of the staples, be clenched upon the bottom face of the insole.

To compensate for the expense incident to employing an insole which can be shouldered 80 or channeled to form an inside support for the upper, I contemplate forming during the shouldering or channeling operation a welt which can be utilized during the outsole attachment in place of the usual separate 85 welt strip, the shoulder or channel, or shoulder and channel, being so formed that the welt strip formed in the shouldering operation will have the grain side of the leather for its upper face. This welt strip 90 will preferably be left attached to the sole at one end whereby the securing of the parts of the shoe together is facilitated and rendered permanent.

The novel shoe produced by the process of 95 the present invention is not claimed herein but forms the subject matter of my co-pending application Serial No. 861,822, filed September 15, 1914.

Other objects and important features of 10 the invention will appear from the following description and claims when considered in connection with the accompanying drawings, in which,—

Figure 1 is a perspective view of the extension insole employed in the manufacture of the improved shoe by the improved process, parts of the insole being shown in sec-

tion to show better the construction of these parts; Fig. 2 shows, in section and side elevation, the mode of lasting the shoe; Fig. 3 is a side elevation, with parts in section, illustrating the completed shoe and the relative positions of the different parts in the completed shoe.

In preparing the extension insole 2, which is shown in Fig. 1, a sole of the outline and size of the outsole 4 to be used in the shoe is channeled in such manner that a welt strip 6 is separated from the sole with the grain side up and that an undercut channel 8 is formed, leaving a channel lip or shoulder 10. This channeling operation preferably extends from a point 12 at the front of the heel-seat part of the sole around the sole to a second point 14 where the channeling knife is withdrawn, leaving the welt strip 6 attached to the sole at this end. After the channeling operation that part 16 of the heel-seat end of the sole which lies within the channeled portion and above the plane of the surface from which the welt strip has been removed is separated from the sole by a splitting machine, or other suitable means, as far forward as the front end of the heel seat, to form a tongue over which the heel end of the upper may be lasted in.

30 The extension insole, having been prepared in the manner shown in Fig. 1, is placed upon the last in such position that the raised central portion 18 of the insole has its edge substantially flush with the bottom edge of the last, or extending slightly beyond the edge but centered upon said last, and the upper when placed upon the last is drawn down and the angle of the upper is forced into the channel or groove 8, thus 35 40 turning the lip 10 up or forcing it against the side or bottom face of the last and forcing the extension edge 20 of the insole down somewhat away from the last. The angle of the upper is preferably forced as far back 45 as possible into the channel or groove 8 and is secured in this position by a fastening, preferably a staple 22 driven through the upper in this angle and through the insole 2 and clenched upon the bottom of the insole. The shoe having been lasted in the 50 manner described, the outsole 4 is placed upon the insole, the welt 6 is laid upon the outturned edge of the upper, and the welt, upper, extension edge of the insole and outsole are united by stitches 26.

In order to provide proper insulation for the foot and to provide a cushion for the insole and also to provide a filler for the space inside the depressed extension edge 20 of the insole, a filling piece 28 is preferably interposed between the insole and outsole before the outsole stitching operation, this filling piece being formed of felt, felt paper or any other suitable filling or cushioning material.

The lasting operation hereinabove described may conveniently be performed with the staple lasting machine shown and described in my co-pending application Serial No. 736,079, filed Dec. 11, 1912, on which Letters Patent No. 1,117,440 were granted November 17, 1914.

Having thus described the invention, what is claimed as new and desired to be secured by Letters Patent of the United States is— 75

1. That improvement in the art of making shoes which comprises cutting from one surface of an extension insole a welt of a width and thickness to provide a shoulder upon said insole which will lie within and support the shoe upper, said welt being left attached at one end to said insole, turning out the lower margin of said upper upon the surface from which the welt has been removed, forcing the angle of the upper into the angle between the shoulder and the surface upon which the upper has been turned out, permanently securing said upper to said insole by inserting staples through the upper in said angle and through the insole, clenching said staples upon the bottom face of the insole, laying the welt upon the outturned upper and securing together said welt, upper, insole and an outsole.

2. That improvement in the art of making stitch-down shoes which comprises cutting from one surface of an extension insole a welt of a width and thickness to leave a shoulder upon said insole which will lie within and support the upper, said welt being left attached at one end to said insole, cutting under said shoulder to form a crease or groove into which the upper may be forced in the lasting operation, assembling said insole and an upper upon a last, turning out the lower margin of the upper upon the surface from which the welt has been removed, forcing the angle of the upper into the undercut crease or groove in the insole, permanently uniting the upper to the insole by fastenings inserted through the upper in said angle and through the insole, laying the welt on the outturned upper, and permanently securing together the welt, upper, insole and an outsole.

3. That improvement in the art of making stitch-down shoes which comprises cutting from the grain side of an extension insole a welt strip of such a width and thickness that a supporting shoulder is formed on said insole to fit inside the shoe upper, one end of said welt being left attached to said insole at approximately the front end of the heel-seat, assembling said insole and an upper upon a last, turning out the lower margin of the upper upon that part of the insole from which the welt has been removed and permanently securing the upper to said insole close to said shoulder, laying 12 13 14 15

the welt upon said outturned part of the upper, and securing together said welt, upper, insole and an outsole.

4. That improvement in the art of making stitch-down shoes which comprises cutting from the grain side of an extension insole a welt strip of such width and thickness that a supporting shoulder is formed on said insole to fit inside the shoe upper,
10 one end of said welt strip being left attached to the insole and said welt strip being separated from the insole substantially about the whole periphery thereof, separating from the body of the sole at the heel-seat
15 end that part of the sole which is left above the surface from which the welt has been removed to form a tongue, assembling said

insole and an upper upon a last, lasting in the heel end of the upper over said tongue, turning out the lower margin of the upper 20 through the shank and forepart upon the surface from which the welt has been removed, securing said upper permanently to said insole close to said shoulder, laying the welt upon the outturned upper, and uniting 25 the welt, upper, insole and an outsole.

In testimony whereof I have signed my name to this specification in the presence of two subscribing witnesses.

ADAM H. PRENZEL.
